WINDOW SHADE

Reynolds Guyer, St. Paul, Minn., assignor to
 Waldorf Paper Products Company, St. Paul,
 Minn., a corporation of Minnesota

Application July 8, 1935, Serial No. 30,242

15 Claims. (Cl. 156—16)

My invention relates to window shades and has for an object to provide a shade constructed of a number of panels hinged together at their edges and simulating in appearance a Venetian blind.

Another object of the invention resides in providing certain of the panels with openings and other of the panels with deflectors shading said openings.

10 A still further object of the invention resides in constructing the shade from a sheet of flexible material folded transversely along spaced parallel lines to form plaits hingedly connected together at their edges.

15 An object of the invention resides in arranging said openings and deflectors at certain of the edges of the plaits or panels.

Another object of the invention resides in constructing said deflectors from the material of the shade separated therefrom in the formation of the openings.

20 Other objects of the invention reside in the novel combination and arrangement of parts and in the details of construction hereinafter illustrated and/or described.

25 In the drawings:

Fig. 1 is a perspective view of a window illustrating an embodiment of my invention applied thereto and disposed in extended position.

30 Fig. 2 is an elevational view of a portion of the structure shown in Fig. 1 and drawn to a larger scale.

Fig. 3 is a cross sectional view taken on line 3—3 of Fig. 1 and drawn to a larger scale.

35 Fig. 4 is a view similar to Fig. 3 showing the shade collapsed.

Fig. 5 is a developed view of the blank from which the shade is constructed.

For the purpose of illustrating my invention, 40 I have shown in the drawings an ordinary double hung window which is indicated in its entirety by the reference character A. This window is constructed with a frame 10 having a casing 11 extending about the same and provided with stops 12, 13, and 14 between which the upper and lower sash 15 and 16 of the window may slide. The window further includes a window sill 17 which forms part of the frame 10 and which extends up against the lower sash 16.

50 My invention may be constructed from paper or any other suitable flexible material which can be scored or otherwise constructed to provide panels hingedly connected together at their edges or the same may be constructed from separate panels of any suitable material attached

together at their edges by means of any suitable hinge construction. In the drawings I have shown the invention as constructed from a sheet of paper and the following description covers this form of the invention.

5 The blank from which my window shade is constructed is shown in detail in Fig. 5 and is indicated by the reference numeral 18. This blank is scored at one end along spaced lines 19 and 21 and adjacent these lines is scored 10 along other lines 22 and 23. The shade is similarly scored at the other end along lines 24, 25, 26, and 27 which correspond to the scores 19, 21, 22 and 23. Between the scores 23 and 26 the sheet is alternately scored along lines 28 and 29 15 which are equally spaced. By means of the various scores, the blank 18 is divided into panels 31, 32, 33, and 34, at the upper end of the sheet with panels 35, 36, 37, and 38 at the lower end of the sheet and into alternate panels 41 and 42 intermediate the panels 34 and 38. The lateral edges of the blank 18 are designated by the numerals 43 and 44 which form the ends of the various panels.

Intermediate the edges 43 and 44 of the blank 25 18 are arranged two rows of holes 45 and 46 which are situated along two vertical zones 47 and 48 of the shade. Adjoining the edges 43 and 44 of the blank are arranged two other zones 51 and 52 which are similar to the zones 47 and 48. 30 The scores 28 extend completely across the sheet while the scores 29 are confined to the zones 47, 48, 51, and 52.

35 In each of the panels 42 is formed a series of openings 53, 54, and 55 which are disposed adjacent the scores 29. These openings are identical in the various panels and only those in the uppermost panel will be described in detail. The openings 53, 54, and 55 are constructed by shearing the panel 42 along longitudinally extending lines 56, 57, and 58 which occupy the entire space between the zones 47, 48, 51, and 52. The panel 42 is further sheared along transverse lines 59 which extend up to the lines 29. By means of this construction extensions 61, 62 40 and 63 are formed on the panels 41 which project downwardly from the lower edges thereof and which are constructed of the material removed from the panels 42 in the formation of the openings 53, 54, and 55. These extensions serve 45 as deflectors as will be presently more fully described, and shade the openings 53, 54 and 55 formed in the panels 42.

50 For the purpose of supporting the shade at the upper end thereof, the panels 31, 32, and 33, 55

are employed which are wrapped about a bar 64. This bar may be constructed of paper, wood or any other suitable material and serves to stiffen the upper structure of the shade and provide a means for attaching the same to the window proper. The panels 31, 32, and 33, are preferably glued or otherwise secured to the said bar. The bar 64 is attached to the header of the stop 14 by means of screws 65 which pass through said bar and the panels attached thereto.

At the lowermost end of the shade is provided another bar 66 constructed similar to the bar 64 and attached thereto by means of the panels 35, 15 36, and 37, the same as at the bar 64. This bar serves as a weight for causing the shade to descend into extended position and in addition serves a purpose which will be presently described in detail.

When the shade is in extended position, the 20 panels thereof occupy inclined positions as shown in Figs. 1 and 3. It will be noted that the openings 53, 54, and 55 are arranged toward the window sashes 15 and 16 and likewise the deflectors 61, 62, and 63 inclined downwardly toward the 25 window sashes in a manner to shade said openings. By means of this construction, light may be indirectly transmitted through the shade and at the same time air passed through the shade for the purpose of ventilation.

30 The movement of the panels of the shade into extended position is limited by means of two tapes 67 and 68 which are attached at their ends to the bars 64 and 66 and intermediate their ends to the edges of the various panels formed by the 35 scores 28. The tapes 67 and 68 are preferably constructed of a relatively thin paper, fabric, sized cloth or some other suitable material which will readily bend or fold. Said tapes may be secured to said panels by wire or fabric stitching or by 40 gluing the same thereto. In the drawings, I have shown wire staples 69 for securing the said tapes to the panels. When the shade is in extended position, the two tapes 67 and 68 are drawn taut; as shown in Figs. 1 and 3 and limit the further 45 extension of the panels. When the structure is collapsed, as shown in Fig. 4, the tapes are doubled back upon themselves to form folds 71 which occupy the position shown in Fig. 4.

For the purpose of raising the shade two draw 50 cords 72 and 73 are utilized which are threaded through the various openings 45 and 46 in the panels of the shade, and also through two eyelets 74 and 75 attached to the bars 54 and 66. The cords are knotted at one end as indicated at 76 to 55 prevent the said cords from passing through the eyelets 75 and slide freely through the openings 45 and 46 and the eyelets 74. When said cords are drawn through the eyelet 74, the bar 66 serves to raise the various panels of the shade and to 60 collapse the same. The draw cords 72 and 73 may be held in position by means of a cleat or any other suitable construction which forming no particular feature of the invention, has not been shown in the drawings.

65 When my invention is installed as shown in Fig. 3 and the shade is in extended position, the deflectors 61, 62 and 63 form continuations or extensions of the panels 41 from which they issue and shade the openings 53, 54, and 55 in the adjoining panels. Due to the fact that the scores 29 do not extend across these deflectors, the said 70 deflectors are integral with the panels from which they issue and when the structure is in either collapsed or extended position, lie in the plane of said panels. When the shade is raised by means

of the draw cords the parts assume the positions shown in Fig. 4, and the shade is entirely out of the way, giving a maximum amount of light through the window.

My invention is advantageous in that an extremely simple and practical construction is provided which may be used for the purpose of a window shade and which when in extended position admits indirect light and permits of the passage of air through the shade. The shade can be 5 constructed at an extremely economical cost and from various kinds of materials. The shade is simple in operation and is not apt to get out of order. By means of the particular opening and deflectors formed in the shade, it becomes unnecessary to adjust the panels thereof as is the case with Venetian blinds. When the shade is constructed of paper, the various panels thereof may be folded into an exceedingly compact form so as not to obstruct any appreciable area of the 20 window. The deflectors in addition to shading the openings, serve to deflect rain and prevent its passage through the shade.

Changes in the specific form of my invention, as herein disclosed, may be made within the scope 25 of what is claimed without departing from the spirit of my invention.

Having described my invention, what I claim as new and desire to protect by Letters Patent is:

1. A window shade comprising a plurality of 30 elongated panels, hingedly connected together along alternate edges thereof, and foldable into juxtaposition or into angular position, said panels when in angular position being arranged in two series, the panels of one series inclining in one 35 direction and the panels of the other series inclining in another direction, the panels of one series having openings therein, and deflectors on the panels of the other series disposed in proximity to said openings.

2. A window shade comprising a plurality of 40 elongated panels, hingedly connected together along alternate edges thereof, one of said panels having an opening therein, and the adjacent panel 45 having a deflector disposed in proximity to said opening.

3. A window shade comprising a plurality of 50 elongated panels, hingedly connected together along alternate edges thereof, one of said panels having an opening therein disposed near a hinged edge thereof, and a deflector formed on the panel hinged to said denoted panel and disposed in proximity to said opening.

4. A window shade comprising a plurality of 55 elongated panels, hingedly connected together along alternate edges thereof, one of said panels having an opening therein disposed near a hinged edge thereof, and a deflector formed on the panel hinged to said denoted panel and extending outwardly therefrom in a manner to shade 60 said opening.

5. A window shade comprising a plurality of 65 elongated panels, hingedly connected together along alternate edges thereof, and foldable into juxtaposition or into angular position, one of said panels having an opening along the upper edge thereof, and a deflector at the lowermost edge of the superimposed panel, said deflector shading said opening.

6. A window shade comprising a plurality of 70 elongated panels, hingedly connected together along alternate edges thereof and foldable into juxtaposition or into angular position, one of said panels having an opening along the upper edge thereof, and a deflector issuing from the lower- 75

most edge of the superimposed panel, said deflector lying in the plane of the panel from which it issues and shading said opening.

7. A window shade constructed of a sheet of 5 flexible material folded transversely along spaced parallel lines to form a plurality of plaits hingedly connected together at their edges, one of said plaits being cut at the marginal portion adjoining one edge thereof along a line parallel to said 10 edge, and along transverse lines extending between said edge and first named cut to leave an opening in said plaits near the denoted edge thereof and to form on the adjacent plait a deflector extending outwardly therefrom.

15 8. A window shade comprising a plurality of elongated panels, hingedly connected together along alternate edges thereof, and foldable into juxtaposition or into angular position, said panels when in angular position being arranged in two 20 series, the panels of one series inclining in one direction and the panels of the other series inclining in another direction, the panels of one series having ventilating openings therein arranged in the same order and the other panels 25 being free from openings at the portions thereof adjacent the openings in said first named panels.

9. A window shade comprising a plurality of elongated panels, hingedly connected together along alternate edges thereof, certain of said 30 panels having ventilating openings therein, said openings being disposed near the hinged edges thereof.

10. A window shade comprising a plurality of elongated panels, hingedly connected together 35 along alternate edges thereof, certain of said panels having ventilating openings therein, said openings extending substantially throughout the width of the shade.

11. A window shade comprising a plurality of 40 elongated panels, hingedly connected together along alternate edges thereof, alternate panels having laterally extending ventilating openings therein, there being a plurality of openings in

each of said panels, said openings falling short of the lateral edges of the shade and being spaced from one another to form vertical bands along the shade free from openings.

12. A window shade comprising a plurality of 5 elongated panels, hingedly connected together along alternate edges thereof, and foldable into juxtaposition or into angular position, said panels when in angular position being arranged in two 10 series, the panels of one series including in one direction and the panels of the other series inclining in another direction, the panels of one series having laterally extending openings therein, said openings being disposed near the outermost edges of the shade. 15

13. A window shade comprising a continuous elongated sheet adapted to be supported from its upper edge, said sheet having a plurality of adjacent sets of superimposed slots constituting 20 ventilating openings, the slots of each set being spaced from the slots of the adjacent sets, and the slots of the outer sets being spaced from the lateral edges of the sheet to leave vertical bands between slots and at the lateral edges of the sheet, and auxiliary supporting means attached to the 25 shade at certain of said bands.

14. A window shade comprising a plurality of elongated panels, hingedly connected together along alternate edges thereof, alternate panels thereof having ventilating openings therein and 30 the others being free from openings.

15. A window shade comprising a plurality of elongated panels, hingedly connected together along alternate edges thereof, said panels having two series of superimposed openings therein for 35 the reception of draw cords, and ventilating openings in certain of said panels, said ventilating openings being disposed to either side of said first named series of openings, and spaced therefrom to provide vertical bands at the locality of 40 said first named openings for connecting said panels together.

REYNOLDS GUYER.
